UNITED STATES PATENT OFFICE.

JAMES F. McELROY, OF ALBANY, NEW YORK, ASSIGNOR TO CONSOLIDATED CAR HEATING COMPANY, OF ALBANY, NEW YORK, A CORPORATION OF WEST VIRGINIA.

HOT-WATER-CIRCULATING SYSTEM.

SPECIFICATION forming part of Letters Patent No. 794,730, dated July 18, 1905.

Application filed April 17, 1902. Serial No. 103,272.

To all whom it may concern:

Be it known that I, JAMES F. McELROY, a citizen of the United States, residing at Albany, county of Albany, and State of New York, have invented certain new and useful Improvements in Steam - Heaters for Hot-Water Systems, of which the following specification and accompanying drawings disclose as an illustration one embodiment thereof, which I now regard as the best out of the various forms in which the principles of my invention may be applied, of which—

Figure 1 is a longitudinal section; Fig. 2, a plan, and Fig. 3 a cross-section.

My invention relates to a steam-drum for heating the water of a hot-water-heating system such as is employed on railway-vehicles. In the drums heretofore generally used in these systems for the most part the steam has been introduced into the drum itself and the water has been passed through an internal tube extending through from one head of the drum to the other. Owing to the difference in expansion and contraction of this tube and the drum it has been difficult to maintain a tight connection at the joints between the tube and the drum-head, and to overcome this difficulty one widely-used expedient has been to provide a stuffing-box between one head of the drum and the said interior tube, which would allow the tube to slide to and fro through the drum-head as it expanded and contracted. Another widely-used expedient has been to make the said tube of corrugated copper, so that it may expand and contract while firmly joined to both ends of the drum. My present invention is aimed to overcome this trouble, and several thousand drums embodying my invention have been put into service and found effective in attaining this object, serving conspicuously to avoid leakages such as occurred with the prior constructions above mentioned. In my present device I pass the water instead of the steam into the drums and I pass it directly through the drum, admitting it at one end and withdrawing it at the other end, so that it has a clear passage from end to end

unobstructed by bends or pockets. I then introduce the steam at one end and withdraw it at the same end by a series of spur-tubes, into which the live steam enters, and by a similar series of jacketing-tubes from which the water of condensation is withdrawn by gravity, both tubes being attached to one end only of the drum. Both series of tubes are mounted on the drum-head, which is separable from the drum-cylinder, so that I am enabled to test every joint between said drum-head and the tubes by a test-pressure of six hundred pounds per square inch before the tubes and joints are inclosed and covered over by the cylinder.

My invention also embraces a drum of the type described which is reversible, so as to be capable of use in either a vertical or horizontal position, and also a drum wherein the pounding due to the intermingling of steam and water in the water-space and also in the steam-space is avoided. To these ends I arrange the entrance port or opening into the drum on the opposite side of the drum-axis from the exit port or opening, the said openings being also at the respective ends of the drum. Then if the drum lies horizontally— as, for example, under the car—the water is admitted at the port below the drum-axis and withdrawn at the port above the drum-axis. If, however, it stands vertically, the route of the water is merely reversed, entering at the end where in the horizontal position it would leave the drum. The steam-ports are similarly arranged with respect to the axis of the drum, but the steam, on the contrary, enters at the upper port and the condensed water leaves at the lower port, while the drum is horizontal. When it is vertical, the steam passes upward through the spur-tubes, and condensing to water in the jacket-tubes the water falls downward to the lower ends of the jacket-tubes, where it is withdrawn. Thus in the vertical position of the drum the steam is, in effect, introduced at the upper level by means of the spur-tubes and the water of condensation is taken off at the lower level. By this means the heated

water and steam are free to rise from the drum into the circulating system of the car and so the steam will separate itself from the water with an avoidance of the pounding. 5 The arrangement of the steam-tubes is also important in that in either position there is, in those tubes also, no intermingling of steam or water, which would cause pounding or would cause the banking up of the water 10 ahead of the steam, with the result of the gradual filling up of the steam-space by water and the subsequent freezing of the water. In my construction the entering steam-tube is jacketed by the condensed-water space 15 and the water-space is drained at its lowest point whether the drum stands vertically or horizontally. Moreover, the steam, by reason of the jacket, remains steam until it emerges from the spur-tube, and then it 20 comes against the water-wall of the jacketing-tube and is condensed into water. So long as it is in the spur-tube it is surrounded by the warmer water of condensation, not by the external water to be heated. This 25 cures the separation of the steam and water of condensation and insures the downward expulsion of the water.

Referring to the drawings, the external drum consists of a tube A, preferably three 30 and one-half to four inches in diameter and about two and one-half feet long, to which is attached at one end, preferably by screwing upon the pipe A, a fitting B, constituting one head of the drum, to which fitting is secured, 35 preferably by screw-threads, the jacket-pipes C, D, E, and F and also the spurs G, H, I, and J. Each of said spurs is open at its outer end and projects into one of the jacket-pipes C, D, E, and F, which pipes are closed by 40 suitable caps at their ends within the drum. Within the fitting B, I also arrange the steam-chamber K, with which the spurs G, H, I, and J communicate. Within the same casting which forms the fitting B, I also arrange 45 the drip-chamber L, with which communicate the jacket-pipes C, D, E, and F. The inflow-pipe M carries steam to the steam-chamber, and the drip-pipe N carries away the drip from the drip-chamber L. As thus arranged 50 the steam conveyed to the drum by the pipe M enters the steam-chamber K, passes through the spurs G, H, I, and J and into the jacket-pipes C, D, E, and F, where it comes in contact with the walls of those pipes which are 55 in contact with the water in the drum A and is condensed. The water of condensation returns by gravity through jacket-pipes C, D, E, and F to the drip-chamber L and thence escapes through the drip-pipe N. The 60 water of condensation is thus formed not at a point near where the steam enters the spur-heating unit, but at a point remote therefrom and adjacent to the locality of its removal—that is to say, in the jacketing-tube. It will 65 be noticed that the pipes are so arranged that

none of them pass completely through the drum and engage with both heads, and all are preferably, as shown, freely and independently expansible. Hence the expansion and contraction puts no strain on any of the 70 joints. The pipes are all carried by the fitting B and can be attached thereto and the joints tested before the drum A is applied to the fitting, so as to cover over and prevent access to the joints. I also avoid, by my construction, brazed or packed joints, such as were required with the corrugated copper-pipe arrangement or the stuffing-box arrangement of the prior art mentioned above. 75 My drum may be placed either in a horizontal or vertical position. In the former case the water will enter at the lower port O and leave at the upper port P, and in the latter case will enter at P and leave at O, since when placed vertically the fitting B must be 80 at the lower end to allow the condensed steam to depart by the outlet from drip-chamber L, as described. The pipes O and P represent the water-circulating system, and the pipe M the source of steam-supply. 85 I need not illustrate the rest of these arrangements, as they are well known in the art, and especially in car-heating systems. The drums are compact and are made into units of the same size, any number of which may 90 be combined in any desired manner in making up the heating system.

I arrange the plugs m and n in openings connected with the chambers K and L, respectively, and on opposite sides of the fitting B from the pipes M and N, respectively, which plugs may, if desired, be removed and the pipes M and N placed therein, the plugs being used to take the place of the space occupied by said pipes, should such change be 100 made. It should also be observed that the drum A communicates with the water-chamber in fitting B, which is considerably 105 larger in diameter than the drum itself. This is to allow of the water flowing freely around the jacket-tubes, which traverse said chamber and which fill the drum in practice somewhat more completely than in the illustration shown in the drawings. It may also be noted that the water-chamber in the drum-head or fitting is located nearest to the drum itself. Back of the water-chamber is the drip-chamber L, the jacket-pipes therefrom traversing the water-chamber, and back of the drip-chamber is the steam-chamber K, 110 from which the spur-tubes project, extending through both the drip-chamber and the water-chamber on their way to the drum. This provides for the convenient access to the interior of the drum of both the water and 115 steam.

What I claim as new, and desire to secure by Letters Patent, is—

1. A steam-heater for a water-circulating system comprising a water-drum having inlet 120

130

and outlet connections with said system, a steam-chamber at one end of said drum having connection with a source of steam-supply, a drip-chamber at the same end of the drum 5 separate from the steam-chamber and having an outlet in its lower portion for water of condensation, a gravity-drained spur jacketing-tube extending from said drip-chamber into the drum and closed at its outer end, 10 and a spur steam-tube extending from the steam-chamber into the jacketing-tube and open at both ends.

2. A steam-heater for a water-circulating system comprising a water-drum having connections with a water-circulating system, a steam-chamber at one end of said drum having connection with a source of steam-supply, a drip-chamber at the same end having an outlet for water of condensation, and a series 15 of heating-spurs extending into the drum from one end and having a uniform distribution throughout its interior, said spurs comprising a series of gravity-drained jacketing-tubes closed at their outer ends and all 20 connected with the drip-chamber, and a series of open-ended steam-tubes inclosed by the jacketing-tubes and all extending from the common steam-chamber, whereby the water in the drum is uniformly heated at a 25 plurality of points.

3. A steam-heater for a water-circulating system comprising a drum having water-inlet and water-outlet, a steam-chamber at one end thereof having a series of spur-tubes projecting 30 into the drum and open at their outer ends, a drip-chamber at the same end of the drum having an outlet from its lower portion for water of condensation and a series of gravity-drained jacketing-tubes extending 35 from said drip-chamber into the drum and inclosing the steam-tubes, said jacketing-tubes having closed outer ends.

4. A steam-heater for a water-circulating system comprising a water-drum with inlet 45 and outlet ports on different levels; a head or fitting at one end of the drum containing three chambers, first a water-chamber communicating with the interior of the drum, second, a drip-chamber for the water of condensation provided with an outlet in its 50 lower portion for said water, and, third, a steam-chamber, a plurality of spur-tubes extending from the head or fitting into the drum and communicating at one end with the said steam-chamber and open at their 55 other ends; and a plurality of gravity-drained jacketing-tubes, each inclosing one of the said spur-tubes and communicating at one end with said drip-chamber but closed 60 at their outer ends respectively.

5. A steam-heater for a water-circulating system comprising a water-drum with inlet and outlet ports on different levels; a head or fitting for said drum containing three cham-

bers, first, a water-chamber communicating 65 with the interior of the drum, second, a drip-chamber for the condensed water having an outlet for the latter, and, third, a steam-chamber; a gravity-drained jacketing-tube extending from the drip-chamber through 70 the water-chamber into the drum and closed at its outer end; and a spur-tube extending from the steam-chamber through both the drip-chamber and the water-chamber into the interior of the jacketing-tube and open 75 at its outer end.

6. A head or fitting for one end of the water-drum of a steam-heater, provided with three chambers located one in advance of another and comprising, first, a water-chamber 80 with an opening adapted to communicate with the drum, second, a steam-chamber provided with spur steam-tubes projecting therefrom through said opening, and, third, a drip-chamber provided with gravity-85 drained tubes jacketing the steam-tubes and projecting therefrom through the said opening, said drip-chamber having an outlet for water of condensation.

7. A steam-heater for a water-circulating system, comprising a water-drum; a detachable fitting therefor having three chambers, to wit: first, a water-chamber communicating with the interior of the drum and of larger diameter than the drum, to provide a 90 water-flow space outside of the tubes and inside the chamber, second, a drip-chamber for the water of condensation having a drip-outlet, and, third, a steam-chamber; a jacketing-tube extending from said drip-chamber through the said water-chamber into the interior of the drum and closed at its outer end; and a spur-tube extending from said steam-chamber into the jacketing-tube and open at its outer end.

8. A reversible steam-heater for a water-circulating system comprising a water-drum having water inlet and outlet ports at different ends and on opposite sides of its axis, separate steam and drip chambers both at the same end of the drum, a steam-inlet to the steam-chamber, a drip-outlet from the drip-chamber draining said chamber in both horizontal and vertical positions of the heater while the water inlet and outlet ports are at 110 different levels, a gravity-drained spur jacketing-tube extending into the drum from said drip-chamber, and a steam-tube extending into the jacketing-tube from said steam-chamber.

9. A steam-heater for a water-circulating system, comprising a drum having steam and drip chambers at the same end connected with the steam-supply and drip-discharge respectively and having water inlet and outlet for the body of the drum connecting with the water-circulating system, and having also a series of freely and independently ex-

pansible gravity-drained spur heating units projecting from one end of the drum into the water-containing body thereof and each having an internal steam-supply channel leading from the steam-chamber and an external condensation return-channel jacketing the same and leading to the drip-chamber.

Signed at Albany, New York, this 12th day of April, 1902.
